MOTOR PUMP UNIT

Richard T. Cornelius, Minneapolis, Minn.

Application May 7, 1942, Serial No. 442,008

12 Claims. (Cl. 172—126)

My invention relates to pumps and particularly to pumps having a variable capacity.

An object of the invention resides in providing an insulating pump and a control device therefor by means of which the volume discharged from the pump may be quickly and accurately varied without direct adjustment of the pump.

Another object of the invention resides in providing a control device adapted to control the number of strokes or pulsations of the pump per unit of time, whereby the capacity of the pump is correspondingly regulated.

My invention utilizes an electrically operated pump and includes a periodically operable control device, together with means for varying the period of operation of said control device.

A feature of the invention resides in constructing the control device with an oscillatory member and in providing a construction for varying the period of oscillation of said member.

Another object of the invention resides in utilizing a weighted arm pivoted to the oscillatory member and movable in a direction to vary the period of oscillation thereof and in further providing means for holding the arm in adjusted position.

Another object of the invention resides in providing a switch operated by the oscillatory member and in employing a circuit controlled by said switch for controlling the operation of the pump.

A feature of the invention resides in providing a simple and effective construction for changing the position of said weighted arm to vary the period of movement of said oscillatory member.

Another object of the invention resides in providing a control device adapted to simultaneously control the operation of a number of pumps.

Other objects of the invention reside in the novel combination and arrangement of parts and in the details of construction hereinafter illustrated and/or described.

In the drawings:

Fig. 1 is a diagrammatic view illustrating the installation of my invention in an aeroplane.

Fig. 2 is a longitudinal elevational sectional view taken through the pump.

Fig. 3 is an elevational cross-sectional view taken substantially on line 3—3 of Fig. 2.

Fig. 4 is a cross-sectional detail view taken on line 4—4 of Fig. 2.

Fig. 5 is a longitudinal elevational sectional view of the control device of the invention.

Fig. 6 is an elevational cross-sectional view taken on line 6—6 of Fig. 5.

Fig. 7 is an elevational cross-sectional view taken on line 7—7 of Fig. 5.

Fig. 8 is a view similar to Fig. 5 showing the parts in altered position.

Fig. 9 is a view similar to Fig. 6 showing the parts in positions corresponding to those shown in Fig. 8.

For the purpose of de-icing aeroplane propellers, it becomes desirable to pump a de-icing liquid such as alcohol along the surfaces of the propeller blades and to vary the amount of liquid furnished thereto. The customary practice has been to utilize a number of variable capacity pumps and to individually change the capacity of each pump to meet the desired requirements.

20 This requires separate adjustment of the pumps and inconvenience and loss of time to the operators. The instant invention provides a construction by means of which a number of pumps may be controlled by a single control device and the output of the pumps simultaneously varied by the adjustment of the single control device.

For the purpose of illustrating the application of my invention, I have diagrammatically shown in Fig. 1 an aeroplane which is indicated by the reference numeral 11. This aeroplane includes a fuselage 12 and wings 13 connected therewith. The cowl of the fuselage is designated by the reference numeral 14. On the wings 13 are mounted two motors 15 and 16 having propellers 17 and 18 driven thereby. The propellers 17 and 18 have a number of blades 19 mounted on a central hub 21. Inasmuch as the construction of the aeroplane forms no particular feature of the invention, the same has merely been shown in diagrammatic form and has not been illustrated in detail, though it can readily be comprehended that the invention is applicable to various types of aeroplanes, as will become evident from the following description.

The invention utilizes a control device 22 which is mounted on the instrument panel 23, accessible from the cowl 14 and two pumps 25 and 26. Inasmuch as both of these pumps are identical, only the pump 25 will be described in detail.

50 The pump 25 is best shown in Figs. 2 to 4, in-

clusive, and consists of a pump unit 10 which comprises a cylinder 11 having a bore 12. This bore receives a reciprocable piston 13. The bore 12 extends through both ends of the cylinder 11 and is closed at its outermost end by means of a flap valve 14 which is seated against a seat 15 formed at the extreme end of the cylinder 11. The piston 13 has a passageway 16 within the same which is closed at its inner end by means of a valve head 17 seated against a seat 18 at the end of the piston. The valve head 17 has a stem 19 which extends along the passageway 16 and has secured to its outer end a cross head 21. A compression coil spring 22 seated against the cross head 21 and against a shoulder 23 is formed in the piston 13 and urges the valve head 17 into closing position. The cross head 21 is provided with a number of passageways 24 through which communication with the passageway 16 on each side of the cross head 21 may be had, so that fluid may travel directly through the passageway 16, past the valve head 17 and into the cylinder chamber 25.

The pump 85 is electrically operated by means of an electromagnet 40. The cylinder 11 is received within a tubular core 26 of ferrous material forming part of the electromagnet 40 which core is provided with an outwardly extending flange 27. A tube 28 of non-ferrous material encircles the core 26 and forms a support for an electromagnet coil 29 which encircles the core 26 and extends considerably beyond the end of the core 26. The magnetic circuit of the electromagnet 40 further includes a sleeve 31 of ferrous material which encircles the coil 29 and is in intimate contact with the flange 27 of core 26. This sleeve is connected to an end plate 34 which has an opening in the central portion of the same indicated at 35 and receiving the end of the tube 28. A tubular armature 36 of ferrous material is slidable within the tube 28 and is adapted to approach the end of the core 26 when the piston reaches the end of its stroke. This armature is attached to the protruding end of the piston 13 and serves to actuate the same. These two parts are held in proper position by means of an inwardly extending flange 37 formed on the inner surface of the armature 36 and corresponding outwardly extending flange 38 formed on the outer circumference of the piston 13, flange 38 being frictionally held in place in the armature 36. The flanges 37 and 38 of the armature 36 and piston 13 are provided with axially extending openings 39 which permit of the passage of fluid past said armature. The armature 36 and the piston 13 are urged into position away from the end of the cylinder 11 having the valve 14 by means of a compression coil spring 41. This coil spring is seated at one end against the flange 38 of piston 13 and at its other end against a shoulder 42 formed on the exterior of the cylinder 11. It will readily become apparent that upon energization of the coil 29, the armature 36 is urged toward the core 26 and movement of the piston 13 occurs in a direction toward the end of the cylinder 11.

The pump unit 10 is mounted in a case 43 which has a cylinder body 44 bored at 45 to receive the sleeve 31, the flange 27 and the plate 34. The unit 10 is held in position within the body 44 by means of a screw 33 which extends through said body and is threaded into the plate 34. The body 44 has two legs 46 issuing downwardly from it which are threaded at 47 to receive attaching screws, not shown, by means of which the case

43 may be attached to any suitable support. The case 43 has formed on it an electrical outlet box 48 which has attached to it an electrical connector 49 which is connected in the electrical system of the invention, as will be presently described. Conductors 51 and 52 within the chamber 53 formed in the outlet box 48 are connected to the coil 29 and serve to energize the same, as will appear.

10 Screwed into the end 54 of the plate 34 is a plug 55 which is internally threaded at 56 to receive a tube connector. This plug has a passageway 57 therein which communicates with the passageway 16 in the piston 13. A neck 58 formed on the inner portion of the plug 55 engages the end of the piston 13 and forms a stop for limiting the movement of said piston away from the valve 14.

15 Screwed in the end of the core 26 opposite the plug 55 is another plug 59. This plug is threaded at 60 to receive a suitable tube connector and has a passageway 61 extending through the same. The inner end of the plug 59 is formed with legs 62 which provide passageways 63 for bringing the passageway 61 into communication with the valve chamber 64 formed in the core 26 at the end of the cylinder 11. The disk valve 14 is disposed within this chamber and is limited in its movement away from the valve seat 15 by means of the legs 62. The valve disk 14 is formed with recesses 65 at its outer edge (Fig. 4) which bring the valve chamber 64 into communication with the chamber 25 within the cylinder 11 when the valve 14 is open. A compression coil spring 66 within the chamber 64 is seated at one end against the valve disk 14 and at its other end against a shoulder 67 formed on the plug 59 and holds the valve disk 14 in closing position.

20 The operation of the pump 85 is as follows: When the coil 29 is energized, a magnetic circuit is established through the core 26, the sleeve 31, the end plate 34 and the armature 36. This causes the armature to move in a direction to close the air gap 68 formed between the end of the said armature and the end of the core 26. Such movement of the armature urges the piston 13 to move along the bore 12 of cylinder 11 and to compress the liquid within the chamber 25. When the pressure in chamber 25 becomes sufficient, valve 14 opens and the compressed liquid passes through the various passageways 65, 63 and 61 and into the tube connected to the plug 59. Upon deenergization of the coil 29, spring 41 urges the armature 36 to move in the opposite direction. Suction within the chamber 25 causes the valve head 17 to open and a fresh charge of liquid to be drawn into the chamber 25. In this manner, liquid is pumped by the pump 85 upon alternate energization and deenergization of the coil 29.

25 The control device 82 is best shown in Figs. 5 to 9, inclusive. This device includes a case 87 which is formed with a back 88 and a cup-shaped wall 89 extending outwardly therefrom. The cup-shaped wall has an opening 91 in it through which extends a threaded member 92 having a flange 93 extending inwardly therefrom and engaging the said back 88 upon the interior surface thereof. A lock nut 94, screwed upon the member 92 and engaging the back 88, holds the member attached to the case 87. A similar lock nut 95 engaging the instrument panel 83 holds the case 88 rigidly attached to the said instrument panel.

30 The control device includes an electromagnet

90 having a core 96 which consists of two legs 97 and 98 connected by a yoke 99. The yoke 99 has an opening 101 through it through which a sleeve 102 is formed on the flange 93 of member 92 extends. This sleeve has a shoulder 103 thereon which engages the yoke 99 adjacent the opening 101 and clamps the core 96 in position within the case 87. The core 96 further includes two screws 104 and 105 which extend through the yoke 99 and which are threaded into pole pieces 106 and 107. Mounted on the said screws are sleeves 108 which hold the parts in assembled relation and which support electromagnet coils 109. Secured to the outermost ends of the legs 97 and 98 is a bar 112 of ferrous material which is attached to said legs by means of screws 113 extending through said bar and screwed into the said legs. This bar also forms a support for a cover 114 for case 87 which is constructed from insulating material and which is attached to said bar by means of screws 115 extending through said cover and threaded into the bar.

Mounted for oscillation within the space within the pole pieces 106 and 107 and the core 96 is an armature indicated in its entirety by the reference numeral 116. This armature has poles 117 and 118 which are spaced from the pole pieces 106 and 107 by means of an air gap 119. The armature 116 has a stub shaft 120 on one end which has secured to it a ball bearing 121 and at its other end a ball bearing 122 which are supported in a manner to be presently described. The armature 116 has a bore 124 therein which opens outwardly through the end thereof opposite the ball bearing 121 and has a radially extending slot 125 formed in the same end thereof which intersects the bore 124. A ball bearing 122 is mounted in and attached to the bar 112. Journaled in the ball bearing 122 is a short shaft 123 which is provided at its end opposite the ball bearing 122 with an enlarged portion 126 which is slidably mounted in the bore 124. This enlarged portion has a radial slot 127 in it and a bore 128 which extends throughout the major portion of the length thereof and which opens exteriorly through the end of the enlarged portion 126. In this bore is slidably mounted a plunger 129 which is seated at one end in a socket 131 in the armature 116. The other end of this plunger is engaged by a compression coil spring 162 which is seated at its other end against a shoulder 163 formed at the end of the bore 128. By means of this construction, the armature 116 is urged to move away from the bearing 122 through the action of the spring 162.

Disposed in portions of the slot 125 near the periphery of the enlarged portion 117 of armature 116 are two arms 134 and 135 which are pivoted to said armature by means of pins 136 which extend jointly through the enlarged portion of the armature and said arms. These arms are provided at their outermost ends with weights 137 which tend to draw the arms radially outwardly as shown in Fig. 8, when the armature 116 is oscillated. The arms 134 and 135 have fingers 138 formed thereon which extend through the slot 127 in shaft 123 and which engage shoulders 160 in said shaft formed by the slot 127. These shoulders limit the outward movement of the arms 134 and 135 and determine the period of oscillation of the armature 116.

Relative axial movement between the armature 116 and the shaft 123 is controlled by means of a mechanism best shown in Figs. 5 and 8. The threaded member 92 which extends through the

panel 83 and supports the case 82 of the invention is formed with a bore 141. Slidably mounted in this bore is a sleeve 142 which is formed with internal threads 143. This sleeve has a flange 140 at its interior end which abuts against the flange 93 on the threaded member 92 and is provided with a removable collar 144 adjacent the end of the threaded member 92 which holds the said sleeve from axial movement within the bore 141. The outer end of the sleeve 142 has secured to it by means of a set screw 145 an operating knob 146 by means of which the sleeve 142 may be rotated. Rotation of the said sleeve is limited to a portion of a revolution by means of a pin 147 attached to the flange 93 on the threaded member 92 which operates in a groove 148 in the periphery of the flange 140 of sleeve 142. Screwed into the threads 143 of the sleeve 142 is a spindle 149 which is formed at its inner end with a cup-shaped member 151 receiving the outer race of the ball bearing 121. This cup-shaped member is slidably supported and held from rotation by means of a number of splines 152 at the outer periphery of said cup-shaped member which operate in similarly formed keyways 153 formed in the sleeve 142. The threads 143 are relatively coarse, being quadruple threads, so that a small movement of the knob 146 will procure appreciable movement of the spindles 149. By means of this construction, the armature 116 is moved in a longitudinal direction, so as to limit the outward movement of the weighted arms 134 and 135 and at the same time, the said armature is supported for oscillation in the bearing 122 carried by the spindle 149.

Formed on the shaft 123 adjacent the bearing 122 is a hub 154. The hub 154 has secured to it a spiral leaf spring 155 which encircles the same. The outer end 156 of this leaf spring is secured to a post 157 which is attached to a spring clip 158. The clip 158 is slidably mounted on a segment 159 which is concentric with the shaft 123 and which is attached to the bar 112 by means of two screws 161. By means of this construction, the spring 155 may be adjusted so that the armature 116 occupies the position relative to the pole pieces 106 and 107 shown in Fig. 9 when the parts are in normal position. When the coils 109 of the electromagnet are energized, the armature 116 is shifted to the position shown in Fig. 7 and the spring 155 tensioned. Upon deenergization of the said coils, spring 155 returns the armature to its normal position shown in Fig. 9.

Operating in conjunction with the armature 116 is a switch indicated in its entirety by the reference numeral 164. This switch comprises two contacts 165 and 166 which are carried on spring arms 167 and 168, respectively. The said spring arms are attached to brackets 169 and 171 which are secured to the inner surface of cover 114 of the case 82 by means of rivets 172. Spring arm 167 is urged into engagement with a stop 173 fixed relative to the bracket 169, while the spring arm 168 is similarly urged into engagement with a stop 174 secured to the bracket 171. The resiliency of the arms 167 and 168 tends to open the switch 164, the parts in open position being shown in Fig. 6. The spring arm 168 has attached to the end thereof a finger 175 by means of which the said spring arm may be urged toward the spring arm 167 to bring the contacts 165 and 166 into contact with one another. Secured to the hub 154 of shaft 123 is an arm 176 which is adapted to engage the finger 175 and to move the spring arm 168 in a manner to cause the con-

tacts 165 and 166 to make contact and to close switch 164.

The operation of the control device 82 is as follows: The coils 109 are connected in series with the switch 164 and a source of electric current. When the electromagnet 90 is deenergized, switch 164 is closed, as shown in Fig. 9. When the circuit through coils 109 is completed, the electromagnet 90 is energized, which causes the armature 116 to be moved from the position shown in Fig. 9 in which the switch 164 is closed and to the position shown in Fig. 6 in which the arm 176 has receded from the finger 175 and permitted the contacts 165 and 166 to separate. As soon as these contacts separate, the circuit through the coils 109 of the electromagnet 90 are deenergized, and the spring 155 moves the armature back to its normal position. By means of this construction, an oscillatory movement of the armature 116 results, the period of said movement being dependent upon the position to which the weight arms 134 and 135 are permitted to move. It will be readily comprehended that when the knob 146 is turned, that the outermost position of the said arms is varied and the period of oscillation of the armature 116 is correspondingly varied. By means of this construction, I am able to procure a variation in the timing period of approximately 1 to 5.

When my invention is used for the deicing of the propeller blades of an aeroplane, the parts are connected as diagrammatically illustrated in Fig. 1. Coils 109 of the control device 82 are connected together and one of the other ends of one of said coils is connected by means of a conductor 177 with the contact 166 of switch 164. The other contact 165 of said switch is connected by means of a conductor 178 with a manually operated switch 179 which, in turn, is connected by means of a conductor 181 with the battery 182 of the aeroplane. The other side of the battery 182 is connected by means of a conductor 184 with the pump 86 which is further connected by means of a conductor 185 with the contact 166 of switch 164. The pump 85 is connected in parallel with the pump 86 by means of two conductors 186 and 187 which, in turn, are connected to the conductors 184 and 185, respectively. The switch 164 is shunted by a resistance 188 and a condenser 189 which are connected in parallel in a circuit 191 which is connected to the conductors 178 and 185 previously referred to.

Alcohol for use for deicing purposes is contained in a container 192 which has connected to it a pipe line 193. This pipe line has disposed in it a valve 194 which, in turn, is connected to two branch pipes 195. Both of these branch pipes are connected to filters 197 which, in turn, have connected to them pipes 198 and 199. These pipes, in turn, are connected to the threads 56 in the plugs 55 of the pumps 85 and 86 which direct the alcohol into the inlet passageways 57 of said pumps. The outlet passageways 61 of said pumps are connected to other conduits 201 which, in turn, are connected to check valves 202. These check valves are connected to the distributor pipe 203 which lead the alcohol to devices used for distributing the same upon the blades of the propellers 77 and 78 and which devices are indicated generally by the reference character 204. Inasmuch as such devices are well known in the art, the same have not been illustrated in detail in this application.

When my invention is used as a deicing system for the propeller blades of an aeroplane, the

same functions as follows: Upon closing the switch 179, the control device 82 is energized and the switch 164 is periodically opened and closed. The period of said control device depends upon the setting of the knob 146. Inasmuch as both of the pumps 85 and 86 are connected in parallel, in a circuit which includes the switch 164, the electromagnets 40 of both of said pumps are simultaneously energized along with the energization of the electromagnet 90 of the control device. Thus, the pumps each make one stroke for each cycle of the control device and a certain amount of alcohol is pumped by each pump to the respective distributing device 204 to which it is connected. It will readily be comprehended that the period of oscillation of the control device 82 is effective to control the number of strokes of the pumps 85 and 86 and thus to control the output of the said pumps. In this manner, the volume of alcohol discharged upon the propeller blades may be accurately and easily controlled at will.

My invention is highly advantageous in that a pumping system is employed in which the capacity of the pump may be varied from extremely low to extremely high limits. With my invention, accurate metering of the liquid pumped can be procured, so that waste of alcohol is overcome and, in addition, the correct amount delivered at all times. With my system, any number of pumps may be controlled by a single control device which may be remotely situated from the pumps and within easy reach of the operator at the instrument board of the aeroplane. The device is extremely compact and may be constructed relatively light, so as to occupy a minimum amount of space on the aeroplane and so as to not unnecessarily increase the weight to be carried by the plane.

Changes in the specific form of my invention, as herein described, may be made within the scope of what is claimed without departing from the spirit of my invention.

Having described my invention, what I claim as new and desire to protect by Letters Patent is:

1. In a timer, a pivoted oscillatory member, a switch, means on said oscillatory member for operating said switch, a spiral spring attached at one end to a part movable with said oscillatory member, a segment, a slide movable along said segment, said spring being attached at its other end to said slide, means for periodically moving said oscillatory member in one direction to tension said spring, said means being controlled by said switch.

2. In a timer, a pivoted oscillatory member, a switch, means on said oscillatory member for operating said switch, a spiral spring attached at one end to a part movable with said oscillatory member, a segment, a slide movable along said segment, means for periodically moving said oscillatory member in one direction to tension said spring, said means being controlled by said switch, a weighted arm pivoted to said pivoted member and movable radially relative thereto and means for limiting the outward movement of said weighted arm.

3. In a timer, a pivoted oscillatory member, a weight carried by said member, means for guiding said weight for movement toward and from the axes of said member, a timing control member, means for guiding one of said two first named members for movement relative to the other, means acting between said timing control member and said weight for limiting the outward movement of the weight, a slidale member, said

pivoted member oscillating relative to said slideable member, means for restraining rotation of said slideable member and rotational means engaging said slideable member and causing axial movement thereof.

4. In a timer, a pivoted oscillatory member, a weight carried by said member, means for guiding said weight for movement toward and from the axis of said member, a timing control member, means for guiding one of said two first named members for movement relative to the other, means acting between said timing control member and said weight for limiting the outward movement of the weight, a slideable member, said pivoted member oscillating relative to said slideable member, means for restraining rotation of said slideable member and threaded means engaging a part movable with said slideable member and upon rotation causing axial movement thereof.

5. In a timer, a support, an oscillatory member, a weight carried by said oscillatory member, means for guiding said weight for movement toward and from the axis of said oscillatory member, a bearing carried by said support, a timing control member mounted in said bearing and oscillating with said oscillatory member, said oscillatory member being axially slideable relative to said timing control member, means acting between said timing control member and said weight for procuring movement of the weight relative to the axis of the oscillatory member upon axial movement of the oscillatory member, and means for imparting to said oscillatory member axial movement.

6. In a timer, a support, an oscillatory member, a weight carried by said oscillatory member, means for guiding said weight for movement toward and from the axis of said oscillatory member, a bearing carried by said support, a timing control member mounted in said bearing and oscillating with said oscillatory member, said oscillatory member being axially slideable relative to said timing control member, means acting between said timing control member and said weight for procuring movement of the weight relative to the axis of the oscillatory member upon axial movement of the oscillatory member, means for imparting to said oscillatory member axial movement, means for imparting to said oscillatory member oscillatory movement in one direction and resilient means acting between said adjusting member and a part fixed relative to the support for imparting to said oscillatory member oscillatory movement in the other direction.

7. In a timer, a support, an oscillatory member, a weight carried by said oscillatory member, means for guiding said weight for movement toward and from the axis of said oscillatory member, a bearing carried by said support, a timing control member mounted in said bearing and oscillating with said oscillatory member, said oscillatory member being axially slideable relative to said timing control member, means acting between said timing control member and said weight for procuring movement of the weight relative to the axis of the oscillatory member upon axial movement of the oscillatory member, a slideable member in axial alignment with said bearing, means carried by said support for guiding said slideable member for axial movement and means for supporting said oscillatory member for oscillatory movement with respect to said slideable member and for causing simultaneous

sliding movement of said slideable member and said oscillatory member.

8. In a timer, a support, an oscillatory member, a weight carried by said oscillatory member, means for guiding said weight for movement toward and from the axis of said oscillatory member, a bearing carried by said support, a timing control member mounted in said bearing and oscillating with said oscillatory member, said oscillatory member being axially slideable relative to said timing control member, means acting between said timing control member and said weight for procuring movement of the weight relative to the axis of the oscillatory member upon axial movement of the oscillatory member, a slideable member in axial alignment with said bearing, means carried by said support for guiding said slideable member for axial movement, means for supporting said oscillatory member for rotational movement with respect to said slideable member and for causing simultaneous sliding movement of said slideable member and said oscillatory member, and a threaded member to impart to said slideable member and oscillatory member axial movement.

9. In a timer, a pivoted oscillatory member having a bore, an arm, a weight carried by said arm, means for pivoting said arm to said pivoted member to cause said weight to move transversely of the axis of said pivoted member upon swinging of said arm, a finger on said arm movable substantially axially upon swinging of said arm and a timing control member disposed within said bore and having a part engaging said finger, said members being guided for relative axial movement, and means for moving one of said members axially relative to the other to limit the outward movement of said weight.

10. In a timer, a pivoted oscillatory member having a bore and a transverse slot communicating with said bore, an arm, a weight carried by said arm, means for pivoting said arm to said pivoted member to cause said weight to move transversely of the axis of said pivoted member upon swinging of said arm, a finger on said arm extending through said slot and into said bore and movable substantially axially upon swinging of said arm and a timing control member disposed within said bore and having a shoulder engaging said finger, said members being guided for relative axial movement, and means for moving one of said members axially relative to the other to limit the outward movement of said weight.

11. In a timer, a pivoted member, a spring connected to said pivoted member, motive means for imparting to said pivoted member intermittent torque impulses, said motive means and spring causing said pivoted member to oscillate about its axis, a weight oscillating with said pivoted member and timing the period of oscillation of said member, means for guiding said weight for movement toward and from the axis of said pivoted member and axially movable means for limiting the outward movement of the weight.

12. In a timer, a support, an oscillatory member, a weight carried by said oscillatory member, means for guiding said weight for movement toward and from the axis of said oscillatory member, a bearing carried by said support, a timing control member mounted in said bearing and oscillating with said oscillatory member, and said oscillatory member being axially slideable

relative to said timing control means, means acting between said timing control member and said weight for procuring movement of the weight relative to the axis of the oscillatory member upon axial movement of the oscillatory member, means for imparting to said oscillatory member axial movement, an electromagnet formed with spaced pole pieces having facing surfaces parallel with the axis of said pivoted member, an armature movable with said pivoted member and 10

5

disposed between said pole pieces, said electromagnet imparting to said oscillatory member oscillatory movement in one direction and resilient means acting between said adjusting member and a part fixed relative to the support for imparting to said oscillatory member oscillatory movement in the other direction, said armature, upon axial movement of said pivoted member, moving longitudinally along said pole pieces.

RICHARD T. CORNELIUS.
